(57) **CLAIM**

The ornamental design for an architectural panel with intersecting paper, as shown and described.

DESCRIPTION

FIG. 1 is a front perspective view of an architectural panel with intersecting paper shown used in a partition structure; FIG. 2 is an enlarged front perspective view of the central area shown in FIG. 1;

FIG. 3 is a left side elevational view taken along line 3—3 of FIG. 4;

FIG. 4 is a front elevation view;

FIG. 5 is a right side sectional view taken along line 5—5 of FIG. 4;

FIG. 6 is a bottom sectional view taken along line 6—6 of FIG. 4;

FIG. 7 is a top sectional view taken along line 7—7 of FIG. 4; and,

FIG. 8 is a rear elevation view.

The broken lines showing environment in the drawings are included for illustrative purposes only and form no part of the claimed design. The outer broken line boundaries in Figures depicting the boundaries of the claimed design indicate that a specific length, width, and thickness form no part of the claimed design and are for illustrative purposes only.
